(**) Term: **15 Years**(21) Appl. No.: **29/560,054****CLAIM**(22) Filed: **Apr. 1, 2016**

An ornamental design for a display screen with transitional graphical user interface, as shown and described.

(51) LOC (11) Cl. **14-04****DESCRIPTION**

(52) U.S. Cl.

FIG. 1 is a front view of the first embodiment of a display screen with transitional graphical user interface;

USPC **D14/486**

FIG. 2 is a second image thereof;

(58) **Field of Classification Search**

FIG. 3 is a third image thereof;

USPC D14/485-495

FIG. 4 is a front view of the second embodiment of the display screen with transitional graphical user interface;

CPC G06T 13/00; G06T 13/80; G06F 3/04845

FIG. 5 is a second image thereof;

See application file for complete search history.

FIG. 6 is a front view of the third embodiment of the display screen with transitional graphical user interface;

(56) **References Cited**

FIG. 7 is a second image thereof;

U.S. PATENT DOCUMENTS

FIG. 8 is a front view of the fourth embodiment of the display screen with transitional graphical user interface; and

FIG. 9 is a second image thereof.

FIG. 10 is a tenth embodiment of a display screen with transitional graphical user interface; and,

FIG. 11 is an eleventh embodiment of a display screen with transitional graphical user interface transitioned from the graphical user interface of FIG. 11.

The broken lines showing the display screen, ovals and arrows form no part of the claimed design. The broken lines showing the remaining elements of the graphical user interface form no part of the claimed design.

D612,860 S * 3/2010 Tarara D14/485

The appearance of the image transitions sequentially between the images shown in FIGS. 1-3, 4-5, 6-7, and 8-9 respectively. This process or period in which one image transitions to another forms no part of the claimed design.
